UNITED STATES PATENT OFFICE.

CHARLES A. MERRILL AND FRANK L. MERRILL, OF NORA SPRINGS, IOWA.

MAIL-BAG FASTENER.

SPECIFICATION forming part of Letters Patent No. 715,495, dated December 9, 1902.

Application filed April 19, 1902. Serial No. 103,822. (No model.)

To all whom it may concern:

Be it known that we, CHARLES A. MERRILL and FRANK L. MERRILL, citizens of the United States, residing at Nora Springs, in the county 5 of Floyd and State of Iowa, have invented certain new and useful Improvements in Mail-Bag Fasteners; and we do hereby declare the following to be a full, clear, and exact description of the invention, such as will enable others skilled in the art to which it appertains 10 to make and use the same.

This invention relates to improvements in fastenings for mail-bags, and is designed, primarily, to secure the ends of the ropes 15 or draw-strings.

The improvement consists of a pair of hinged plates having formed in one side ways for the reception of the designating-card and on the companion plate a slot is provided to 20 receive a staple, whereby a padlock or the like may be used to effectually prevent unauthorized persons from gaining access to the bag.

It is our purpose to construct a fastening 25 whereby the ends of the ropes will be securely clamped thereby and utilize the padlock-staple as a temporary means of fastening the rope between the hinged members.

Many other objects and advantages will be 30 hereinafter referred to, and be particularly pointed out in the claims.

In the drawings, Figure 1 is a perspective view of a mail-bag, showing the application 35 of our invention. Fig. 2 is a face view looking from the opposite side. Fig. 3 is a vertical transverse section, and Fig. 4 is a perspective view of the fastener thrown open.

The numeral 1 indicates a mail-bag, 2 the draw-strings thereof, and 3 our improved fastener.

The fastener comprises two members 4 and 5, hinged as at 6. The member 4 has a lip 7 at its outer end which is provided with two openings 8 and two parallel ways 9 on each 45 side to receive the ordinary designating-card 9^a, and swiveled intermediate these ways is a staple or eye 10. The member 5 is approximately the same shape as the member 4 and is provided with a slot 11 to receive the staple 10, and at its opposite end and on the inner side is a corrugated surface 12, and adjacent thereto is a perforation 13. Extending

along the inner edges of the member 5 are parallel ridges 14 to insure the rope being confined between the members. 55

The draw-strings 2 after they have been passed through the eyes of the mail-bag, as shown in Fig. 1, are passed through the perforation 13 in the member 5 and openings 8 in the member 4 and are knotted. The mail-bag having been filled and it is desired to close the same the member 5 is swung down on the strings, the staple or eye 10 passing freely through the slot 11, whereupon said eye is given a half-turn, which locks the two 65 members in a closed position. When the two members are thus closed, it is evident the corrugated surface 12 will bite into the rope and prevent its slipping, and in addition thereto there is a binding action between the 70 walls of the slot 13 and the hinge 6, and to further insure the rope being confined in case it should buckle when being applied the ridges 14 have a tendency to keep said rope within its bounds. The card is now applied 75 in the ways 9, and after the padlock 18 is fastened in the eye 10 the bag is ready to be shipped.

It will therefore be seen that we provide a mail-bag fastener which will enable the operators to more readily do the work and at 80 the same time add to their convenience and operation. A further advantage is in the fact that a bag may be temporarily fastened with considerable ease and with as much 85 safety as when the padlock is applied. The invention also is capable of being used when the ropes are wet or frozen, which is a cause of no little inconvenience in handling the mail-bags of the type now used. 90

The invention is simple in construction, durable in character, and its advantages will be appreciated by those skilled in the art to which it appertains.

Having thus described the invention, what 95 is claimed as new is—

1. A fastening for holding the rope of mail-bags, comprising a pair of hinged members, one of the members being provided with an opening adjacent to the hinge for the passage of the rope or the like and the other member having an opening a distance from the hinge for the passage of the said rope, an engaging surface on one of the members for 100

gripping the rope when the members are closed, and means for locking the members together, substantially as described.

2. A fastener for the holding-rope of mail-bags, comprising a pair of hinged members, one of said members having a pair of openings for the passage of the rope, a companion member being formed with a single opening for the reception of the rope, a corrugated surface adjacent said single opening, and means for locking the two members together, substantially as described.

3. A fastening for holding the rope of mail-bags, comprising a pair of hinged members, one of the members being provided with an opening adjacent to the hinge for the passage of the rope or the like and the other member having an opening a distance from the hinge for the passage of the said rope, an engaging surface on one of the members for gripping the rope when the members are closed, longitudinal ridges applied to one of

said members for keeping the rope within bounds when the members are closed, and means for locking the members together, substantially as specified. 25

4. A fastening device for the rope of mail-bags, comprising a pair of members hinged together, one of said members having a lip at one end which has formed therein a pair 30 of openings, a staple swiveled to the said member, the other member having an opening at one end and a corrugated surface adjacent said opening, a slot being formed for the passage of the staple, substantially as set 35 forth.

In testimony whereof we affix our signatures in presence of two witnesses.
